UNITED STATES PATENT OFFICE.

FREDERICK W. WAKEFIELD, OF VERMILION, OHIO, ASSIGNOR TO THE F. W. WAKEFIELD BRASS CO., OF VERMILION, OHIO, A CORPORATION OF OHIO.

FLASH LAMP.

1,408,664.

Specification of Letters Patent.

Patented Mar. 7, 1922.

Application filed March 29, 1920. Serial No. 369,788.

To all whom it may concern:

Be it known that I, FREDERICK W. WAKEFIELD, a citizen of the United States, and a resident of Vermilion, county of Erie, and State of Ohio, have invented a new and useful Improvement in Flash Lamps, of which the following is a specification, the principle of the invention being herein explained and the best mode in which I have contemplated applying that principle, so as to distinguish it from other inventions.

The present invention relates to flash lights of the type in general use for household and other purposes where a light is desired for a short length of time. In the present device a light of this character is combined with certain other advantageous features which make the light particularly suitable for use with and around automobiles, motorboats and the like where a warning signal or colored light is at times very desirable. Furthermore, provision is made so that the battery can not be short circuited by metallic contact from the outside so that the lamp may be carried in a tool box or in a pocket with tools. To the accomplishment of the foregoing and related ends, said invention, then, consists of the means herein-after fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a vertical longitudinal section through the lamp; Fig. 2 is a broken similar section showing the parts in the second operating position; Fig. 3 is a section on the line 3—3 of Fig. 1; and Fig. 4 is a section of a detail on the line 4—4 of Fig. 1.

In the lamp shown there is provided the usual casing 1 made of fibre or other insulating material in which is mounted the battery 2 here shown as a two cell battery having a top central contact 3 and a bottom contact 4. At the bottom the casing is provided with a threaded sleeve 5 riveted or otherwise secured to the casing, and a thread cap 6 engages with such sleeve to close the casing, a spring 7 being inserted between the interior surface of the cap and the bottom of the battery. This spring also makes electrical con-

tact with the pole of the battery which is the metallic bottom of the cell and connects such pole with the sleeve 5, as well as maintaining the battery in position in the casing.

In the casing slightly above the top of the battery is mounted a plate 8 which is provided with a depending annular flange 9, the flange being curved slightly and fitting in a groove 10 formed in the casing. This plate is cut away at one side to allow the switch mechanism to be inserted as will be hereinafter more fully described.

Along the interior of the casing and in electrical contact with the sleeve 5, is mounted a contact strip 12 which, as shown, is secured to the sleeve 5 by a rivet 13, and at its top to a switch-carrying plate 14 which is secured to the casing wall. This plate 14 covers a suitable slot 15 in the casing wall and is likewise slotted as at 16 to allow movement of the switch handle or knob 17.

The plate 8 in the casing has a central aperture 20 through which a contact bolt 21 is mounted, the bolts being insulated from the plate by a disk 22 and being held in place by means of a nut 23 which bears against the disk. The extending end 24 of the bolt contacts with the upper central contact 3 of the battery as shown. Surrounding the bolt is a metallic sleeve or socket member 25 which is hollowed out and which fits snugly in the aperture in the plate 8. This socket is provided with an inwardly extending annular shoulder 26 on which is mounted an apertured insulating disk 27 through which the bolt 21 passes and which centers the bolt and prevents it from coming in contact with the socket. The socket is interiorly threaded above the shoulder 26 to receive the lamp bulb 30, the bottom contact 31 of which is in engagement with the head 33 of the central bolt. The exterior of the socket is of greater diameter at the top than at the bottom, an inclined shoulder 34 being formed as best shown in Figs. 1 and 2.

At the top of the casing is mounted a cylindrical shell 35 which is riveted or grommeted to the casing, and this shell has a threaded upper edge 36 which is fitted by a threaded cap 37 having an inturned flange 38 which is adapted to hold the glass closure 39 in place. Within the shell is mounted a reflector 40 which, as shown, is provided with a central aperture 41 through which the light socket extends.

Through the slot 15 in the casing wall is mounted the switch knob or handle. This handle consists of a screw 42 which extends outwardly through an aperture 43 in a flange 44 of an inwardly extending arm 45, there being a nut forming the knob 17 mounted exteriorly of the casing in threaded engagement with the screw 42. A set screw 46 is also mounted through the nut so as to contact the end of screw 42 to maintain the nut securely in position thereon. As shown, the plate 8 is provided with a raised portion or hump 47 which is adapted to fit the curved under surface of the nut so as to tend to maintain the nut in position on the hump, this being the neutral position of the knob.

The arm 45 is provided at its inner end with a metal ring which is adapted to carry a sleeve or cylinder 49 of colored transparent material such as glass or the like. This sleeve encircles the socket and bulb and is movable through the aperture in the reflector. The switch handle is, of course, in electrical connection with the bottom contact of the battery through the strip 12 and the plate 14 so that the arm and ring are electrically connected to one battery contact. In the downward position of the knob shown in Fig. 1 the arm and ring closes the electrical circuit through the plate 8 and the socket to the outside threads of the bulb, the bottom contact of the bulb being always in contact with the other side of the latter through the bolt 21. When in neutral position the ring is spaced away from both the plate 8 and the socket 25, but when the arm is raised to the position shown in Fig. 2, the ring contacts the socket at the point where the socket increases in diameter again closing the circuit.

When contact is made by moving the handle down, that is into the position shown in Fig. 1, the colored sleeve is retracted and the flash light gives the usual white light, but when the knob is raised the sleeve is moved upwardly encircling the bulb so that the color of the ray reaching the reflector is changed, thus giving a colored light. Preferably the sleeve will be made of red or other colored glass so that a warning signal may be given if desired.

The present mechanism presents the added advantage of having a flash light which can not be short circuited from the outside. The reflector and top cap is at all times insulated from the bulb and thus it is only possible to complete the circuit by moving the sleeve. The outside metallic elements of the lamp are all normally in circuit with one battery pole and thus the mere bridging of the metallic parts does not complete the circuit and the battery can not accidentally be discharged.

Another feature is having the switch member connected to the sleeve so that the con-

tact is made either in raised or lowered position, no separate setting of the colored sleeve being necessary. The sleeve always extends upwardly into the opening in the reflector, thus effectually insulating the reflector from the socket or bulb at all times.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a flash lamp, the combination of a battery casing, a switch knob in an electrical connection with one battery pole and movably mounted on said casing, a socket mounted in said casing and adapted to receive a lamp bulb, a contact member mounted in said socket but insulated therefrom, said member making electrical contact with one terminal of the bulb and the pole of the battery, an arm connected to said switch knob and movable therewith and adapted to make electrical contact with said socket to close the electric circuit through said lamp in two positions of said switch member.

2. In a flash lamp, the combination of an insulating casing having a slot therein, a switch knob mounted exteriorly and movable in such slot, said knob being electrically connected to one battery pole, a plate mounted in said casing, a lamp bulb receiving socket mounted on said plate and electrically connected thereto, said socket having a central aperture, a contact screw mounted centrally through said socket and said plate and insulated therefrom, said screw making electrical contact with the other pole of the battery and with one terminal of the lamp bulb, a contact arm connected to said knob and extending inwardly and adapted to contact said plate in one position of said knob and to contact said socket in another position to close the electrical circuit through said bulb in either of two positions of said knob.

3. In a flash lamp, the combination of an insulating casing having a slot therein, a switch knob mounted exteriorly and movable in such slot, said knob being electrically connected to one battery pole, a plate mounted in said casing, a lamp bulb receiving socket mounted on said plate and electrically connected thereto, said socket having a central aperture and having its upper portion of larger diameter than its lower portion, a contact screw mounted centrally through said socket and extending below said plate and insulated from both, said screw making electrical contact with the other pole of the battery and with one terminal of the lamp bulb, a contact arm connected to said

1 knob and movable therewith, said arm being
2 adapted in its normal position to be spaced
3 from said socket but adapted to contact said
4 socket in one position of said knob and
5 said plate in another position of said knob
to close the electrical circuit through the
bulb.

4. In a flash lamp, the combination of an
10 insulating casing adapted to receive a bat-
tery, said casing having a slot therein, a
switch knob mounted in such casing and
adapted to move in such slot, said knob
being in electrical contact with one battery
pole, a plate mounted in said casing ad-
15 jacent said slot, said plate having a cen-
trally located aperture, a hollow lamp bulb
receiving socket mounted on said plate and
electrically connected thereto, a contact
screw mounted through such apertures in
20 said socket and plate and insulated from
both, said screw being normally in contact
with the other pole of said battery and one
terminal of the lamp bulb, and an arm con-
nected to said knob and extending interi-
25 orly of said casing and adapted to be nor-

mally spaced from said socket and said
plate, but being adapted to be moved into
contact either with said plate or said socket
to close the electrical circuit through said
lamp bulb.

5. In a flash lamp, the combination of a bat-
tery casing, a reflector mounted at one end
of said casing, said reflector having a cen-
tral aperture, a lamp bulb receiving socket
mounted in said casing and extending 35
through such aperture in said reflector and
leaving an annular space between said re-
flector and said socket, a transparent colored
sleeve movably mounted through such an-
nular space and adapted in one position 40
to surround said bulb, a switch knob mov-
ably mounted on said casing, said sleeve be-
ing operatively connected to said switch
knob and movable therewith, said knob be-
ing adapted to close the electrical circuit 45
through said bulb in both the extended and
retracted positions of said sleeve.

Signed by me this 25th day of March,
1920.

FREDERICK W. WAKEFIELD.
